SEDGWICK N. WIGHT, OF ROCHESTER, NEW YORK, ASSIGNOR TO GENERAL RAILWAY SIGNAL COMPANY, OF GATES, NEW YORK, A CORPORATION OF NEW YORK.

SIGNALING SYSTEM FOR SINGLE-TRACK RAILWAYS.

1,300,082.

Specification of Letters Patent.

Patented Apr. 8, 1919.

Application filed December 7, 1915. Serial No. 65,460.

To all whom it may concern:

Be it known that I, SEDGWICK N. WIGHT, a citizen of the United States, and a resident of the city of Rochester, in the county of Monroe and State of New York, have invented a new and useful Signaling System for Single-Track Railways, of which the following is a specification.

This invention relates to electrically operated signaling systems for governing railway traffic, and more particularly to block signaling systems for single track railways of the type commonly known as absolute permissive block signaling systems.

Heretofore, signaling systems for single track railways, such as disclosed, for example, in my prior application, Serial No. 753,892, filed March 13th, 1913, have been devised to afford adequate protection against head on and rear end collisions, without unnecessarily restricting the movement of the trains. Although a system such as disclosed in the prior application above mentioned satisfies practically all of the requirements for safety and facility, there is one unusual movement which a train may make under certain traffic conditions in which the trains are not as fully protected as they might be. To illustrate, when a train, having entered a stretch of single track between passing sidings, changes the direction of its movement for some reason and attempts to return to the siding from whence it came, the control of the signals are not designed to take care of a move of this character; and it is possible, as fully explained hereinafter, to have two trains enter the same track section both traveling under caution signals. This invention is in the nature of an improvement upon the signaling system disclosed in my prior application above mentioned, and deals particularly with the unusual train movement above described.

One of the objects of this invention is to devise a signaling system for single track railways which will afford adequate protection for a train which has entered a stretch of single track and attempts to make a reverse movement back to the siding from whence it came.

A further object of this invention is to devise a signaling system for single track railways in which a train making a reverse movement of the character above mentioned

and other trains near it will be properly protected by the system, without unnecessary delay.

A still further object of this invention is to devise a signaling system which will attain the above mentioned objects and other objects, which will more fully appear hereinafter, by means of controlling devices and circuits arranged and constructed in accordance with the principles of railway signaling found to be safe and reliable.

Other objects and advantages will appear as the description of the invention progresses, and the novel features of the invention will be particularly pointed out in the appended claims.

Generally stated, the invention consists in the parts and in the arrangements and combinations of parts, together with the electrical controlling circuits therefor, which are fully set forth hereinafter.

To enable a clear understanding of the nature and utility of this invention, there is illustrated in the accompanying drawing part of a complete signaling system for single track railways, and the circuits and controlling devices with which this invention more particularly deals are combined with this system. It is to be understood, however, that the particular application shown in the drawing is representative of only one physical embodiment of the means contemplated by this invention, and that this invention can be applied to other signaling systems of appropriate construction.

In describing the invention in detail, reference is had to the accompanying drawing, wherein I have illustrated a preferred physical embodiment of my invention, and wherein like characters of reference designate corresponding parts throughout the several views, and in which:

The figure is a diagrammatic view of a portion of a stretch of single track adjacent to one passing siding, and shows the signals, controlling devices and controlling circuits therefor, which constitutes a practical signaling system suitable for this portion of the trackway, the system illustrated in this figure being founded on the disclosure in my prior application above mentioned, and being merely a re-arrangement of the location of the signals and controlling circuits fully shown and described in said prior applica-

tion; and this figure also illustrates the particular features of this invention applied to such a system.

Referring to the accompanying drawing, 5 the two track rails 1 and 2 of the stretch of single track adjacent to the passing siding S are divided by insulating joints 3 into a series of track sections A, B, C, D and E, of which there are shown three complete track 10 sections, B, C and D, with the end portions of the two adjacent track sections A and E. Each of these track sections has a track battery, 4 connected across the track rails 1 and 2 at one end of said section, and at the other 15 ends of said sections, track relays 9, 10, 11, 12 and 13 are connected. The track battery 4 and the track relay of each of said track sections, together with the track rails thereof, constitute the well known normally 20 closed track circuit, the operation of which will be clearly understood by those skilled in the art, without further description. Traffic over this stretch of single track may be in either direction, as indicated by the arrows 25 X and Y.

At the right-hand end of the track section A is located a signal 6 for governing traffic in the direction indicated by the arrow X; and located at the right-hand end of the 30 track section B is another signal 7 for governing traffic in the same direction. At the left-hand end of the track section B is located a signal 5 for governing traffic in the direction indicated by the arrow Y, and at 35 the right-hand end of the track section D is located another signal 8 governing traffic in the same direction. The signal 6 at the entrance to the stretch of single track, for governing traffic in the direction indicated 40 by the arrow X, is of the type commonly known as an absolute signal; whereas the other signals 5, 7 and 8 are of the type commonly known as permissive signals. The characteristics of these different kinds of 45 signals are well known in the art, and it is deemed unnecessary to further discuss the significance of these different signals, or to describe in detail the mode of causing these signals to assume different aspects, so as to 50 enable the engineer to differentiate between them, since it is obvious that this invention is in nowise dependent upon the particular character of signals used.

The signals illustrated are of any well 55 known or suitable type of semaphore signal, adapted for use either in single or double track signaling systems. This type of signal primarily comprises an operating motor of appropriate construction for moving the 60 semaphore from a biased position, which may be termed the stop or danger position to one or more operated positions; and further comprises means to retain the semaphore in its operated position or positions. 65 In the particular embodiment of the inven-

tion illustrated, the semaphore signals are assumed to be three-position signals, that is, these signals have a vertical or 90 degree position, indicating "full clear" or "proceed at unlimited speed"; an inclined or 45 degree position indicating "caution" or "proceed at limited speed"; and a horizontal or zero degree position indicating "stop" or "danger". However, this invention is fundamentally in nowise dependent upon three- 70 position signals, and may be used, without material change or modification, with two two-position signals arranged as home and distant signals, instead of three-position signals. 75

Associated with each of the signals 5, 6, 7 and 8 is a relay, hereinafter termed a line relay, said relays for said signals being designated 14, 15, 16 and 17 respectively. Associated with each of the signals 6, 7 and 8 80 is a relay, hereinafter termed a stick relay, said stick relays for said signals being designated 18, 19 and 20; and also associated with each of said signals is a suitable source of electric current, as a battery, said batteries being designated 21, 22, 23, and 24. Also associated with each of the signals 6, 85 7 and 8 is a pole changing circuit controller, which is arranged to be operated in any suitable way by the movement of the corresponding signal, said pole changing circuit controllers being designated 25, 26 and 27. Each of these pole changing circuit controllers 25, 26 and 27 is in the position 90 shown in the drawing when the corresponding signal is in its 90 degree or proceed position, and said circuit controller remains in this position even after the respective signal moves to its 45 degree or caution position, but shifts quickly to its other position (indicated by dotted lines on the drawing) 95 when the corresponding signal moves from its caution position to its stop position, said circuit controller remaining in its other position 100 so long as the corresponding signal remains in its stop position. Associated with each of the signals 6, 7 and 8 is another circuit controller, which is represented according to established convention, said circuit controllers being designated 28, 29 and 30. 105 110 respectively. Each of these circuit controllers is closed during the movement of the corresponding signal from its vertical proceed position to a position near its caution position, the exact extent of the angular 115 movement of the corresponding signal during which said circuit controller is closed, being dependent upon the operating characteristics of the signal and its controlling relays, the purpose of these circuit controllers being more clearly set forth hereinafter. 120 Associated with the signal 5 is a similar circuit controller 131 which is closed when said signal 5 is in its 90 degree or 45 degree positions or in any intermediate position, but 125 130

which is open in the positions of the signal 5 between 45 degrees and zero degrees.

Although certain relays are herein designated as track relays, certain others as line relays and certain others as stick relays, these designations are chosen merely for the sake of convenience, and it is to be understood that there is no essential difference in reality between the relays so designated, since each of these relays are of any of the well known or ordinary types used for signaling purposes; and any distinction between these relays is due, not to differences in their construction, but rather to the different uses to which they are put.

Associated with the signal 5 is a pole changer magnet 32 having two armatures 33 and 34 arranged with appropriate contacts and connections to reverse the polarity of the connection between the battery 21 and a certain circuit hereinafter traced.

Extending the full length of the track-way protected by the signaling system, is a common wire 35, and for convenience, certain of the circuits hereinafter traced will be traced from the common wire 35 at one point back to the common wire at another point, it being obvious that this common wire serves to complete these circuits.

In order to enable a clear understanding of the nature and utility of this invention, without, however, attempting to describe in detail the circuits and operation of the single track signaling system shown and described herein, since that signaling system is substantially the same as the system shown and described in my prior application hereinbefore mentioned, a brief general description of the operation of the system disclosed herein will be given, the circuits which have special significance with regard to this invention being set forth in detail.

Considering the operation of the system and disregarding for the present the particular improvement embodying this invention, assume that a train enters the stretch of single track from the passing siding S traveling in the direction indicated by the arrow X. When the train enters the track section B, the track relay 10 will be deenergized, as will be clearly understood by those skilled in the art of railway signaling, and its armature 40 will drop and interrupt the circuit which normally energizes the line relay 15, said circuit being as follows:

Circuit number one.

Commencing at the common wire 35, conductors 36, 37 and 38, line relay 15, conductor 39, armature 40 of the track relay 10 in its upper position, conductors 41 and 42, armature 43 of the line relay 16 in its upper position, conductors 44, 45 and 46, upper conducting arm of the pole changing circuit controller 26, conductors 47¹ and 48¹, battery

23, conductors 49¹, 50¹ and 51¹, lower conducting arm of the pole changing circuit controller 26, conductor 52, armature 53 of the stick relay 20 in its lower position, and conductors 54 and 55 back to the common wire 35.

The deenergization of the line relay 15 causes its armature 61 to drop and break the circuit which normally holds the signal 6 in its 45 degree or caution position, said circuit being as follows:

Circuit number two.

Commencing at the battery 22, conductors 48 and 60, armature 61 of the line relay 15 in its upper position, conductors 62 and 63, signal 6 and conductors 64, 50 and 49 back to the battery 22.

The armature 61 also controls the circuit for operating the signal 6 to its 90 degree or proceed position and for holding it in that position, said circuit being as follows:

Circuit number three.

Commencing at the battery 22, conductors 48 and 60, armature 61 of the line relay 15 in its upper position, conductors 62 and 65, polar armature 66 of said line relay 15 in its closed position, conductor 67, signal 6 and conductors 64, 50 and 49 back to the battery 22.

When the train enters the track section B and causes the deenergization of the track relay 10, the armature 78 of said track relay breaks the normally closed circuit for energizing the line relay 17, and remembering that the train is still on block A and the pole changer magnet 32 is deenergized as explained in my prior application, said circuit is as follows:

Circuit number four.

Commencing at the common wire 35, conductors 55, 68 and 69, line relay 17, conductor 70, armature 71 of the track relay 12 in its upper position, conductor 72 and thence by either one of two paths, one path being along conductor 73 through armature 74 of the auxiliary relay Z in its upper position and conductor 56 to conductor 75, the other path being along conductor 90 through armature 91 of the stick relay 19 in its lower position and conductor 92 to the conductor 75, and thence in either case through armature 76 of the track relay 11 in its upper position, conductor 77, armature 78 of the track 10 in its upper position, conductor 79, armature 80 of the stick relay 18 in its lower position, conductors 81, 82 and 83, armature 34 of the pole changer magnet 32 in its lower position, conductors 84 and 85, battery 21, conductors 86 and 87, armature 33 of the pole changer magnet 32 in its lower position and conductor 88 back to the common wire 35.

The function of the two conducting paths

arranged in parallel and controlled respectively by the armature 74 of the auxiliary relay Z and the armature 91 of the stick relay 19, will not be considered at this time 5 but will be fully explained hereinafter.

The deenergization of the line relay 17 causes its armature 61² to interrupt the circuits which operate and hold the signal 8 in its 45 degree and 90 degree positions, said 10 circuits being easily traced by analogy to circuits numbers two and three hereinbefore traced, whereby the signal 8 is caused to assume its zero degree or stop position. The deenergization of the line relay 17 also causes 15 its armature 106 to drop and interrupt a circuit which controls the line relay associated with the next signal to the right of the signal 8 and governing traffic in the same direction. Only part of this last-mentioned circuit is 20 shown in the accompanying drawing, said circuit being analogous to circuit number one for the line relay 15 and being apparent to those skilled in the art by a consideration of the part shown, which is as follows: commencing 25 at the common wire 35, conductors 100 and 101, armature 102 of the stick relay 19 in its lower position, conductor 103, lower conducting arm of the pole changing circuit controller 27, conductors 51², 50² and 49², battery 24, conductors 48² and 47², upper conducting arm of the pole changing circuit controller 27, conductors 46², 104 and 105, armature 106 of the line relay 17 in its upper position, conductors 107 and 108, armature 109 30 of the track relay 13 in its upper position and conductor 110.

The deenergization of the above mentioned line relay (not shown) which is associated with the signal next to the right of the signal 40 8 and governing traffic in the same direction, in turn causes the deenergization of the line relay associated with the next signal to the right of that signal, and so on through the stretch of single track up to and including 45 the absolute signal governing the entrance of trains upon the stretch of single track from the next right hand passing siding.

From the foregoing it can be seen that 50 when the train in question first enters the track section B in the stretch of single track, the signal 6 behind it assumes its stop or danger position, and all of the opposing signals, such as 8, are also caused to assume 55 their danger or stop positions.

As the train in question proceeds and enters the track section C, it causes the deenergization of the track relay 11. The dropping of the armature 76 of the track 60 relay 11 opens another break in the circuit number four for controlling the line relay 17, so as to hold the signal 8 and the other signals to the right thereof governing traffic in the same direction in their danger or

stop positions. The dropping of the armature 61³ of the track relay 11 interrupts a circuit which normally energizes the line relay 16, said line relay 16 being controlled by the track relays of the track sections between the signals 7 and the next signal to 70 the right governing traffic in the same direction, and the line relay, corresponding to the line relay 16, which is associated with said signal to the right. Only part of the controlling circuit for the line relay 16 is 75 shown but this circuit may be readily determined from analogy to circuit number one for the line relay 15. The part of the circuit for the line relay 16 which is shown is as follows: commencing at the common 80 wire 35, conductors 100 and 111, line relay 16, conductor 112, armature 113 of the track relay 11 in its upper position, conductor 114, armature 115 of the track relay 12 in its upper position, conductor 116, armature 117 85 of the track relay 13 in its upper position and conductor 118.

The deenergization of the line relay 16 causes its armature 61¹ to drop and interrupt the circuits, analogous to circuits numbers two and three, which operate and hold the signal 7 in its 45 degree and 90 degree positions thereby causing said signal 7 to assume its zero degree or stop position.

When the track relay 11 was deenergized, 95 the signal 7 was in its 90 degree or proceed position; and during part of the movement of said signal 7 to its zero degree or stop position a circuit for energizing the stick relay 19 is established as follows:

Circuit number five.

Commencing at the battery 23, conductors 48¹ and 120, circuit controller 29, conductor 121, armature 122 of the track relay 11 105 in its lower position, conductors 123 and 124, stick relay 19, conductor 125 and thence by either one of two paths, one of said paths being along conductor 126, armature 127 of the track relay 12 in its upper position and 110 conductors 128, 129 and 49¹ back to the battery 23; the other of said paths being along conductor 130, circuit controlling arm 131 and conductors 132, 129 and 49¹ back to the battery 23.

The circuit controlling arm 131 is operatively connected to the signal 8 and is constructed so as to be closed while the signal 8 is in its zero degree or stop position and to be opened when the signal 8 is in any one 120 of its other positions. In the case under consideration, when the train in question enters the track section C, the signal 8 is in its zero degree or danger position for the reasons hereinbefore explained, so that the 125 circuit number five for the stick relay 19 is closed.

After the stick relay has been energized,

it is maintained energized by the following circuit.

Circuit number six.

- 5 Commencing at the battery 23, conductors 48¹ and 60¹, armature 61¹ of the line relay 16 in its lower position, conductor 135, armature 136 of the stick relay 19 in its upper position, conductors 137 and 124, 10 stick relay 19, conductor 125 and thence along either of the conducting paths arranged in parallel and set forth hereinbefore in circuit number five, back to the battery 23.
- When the stick relay 19 is energized its 15 armature 139 in its upper position establishes a shunt comprising conductor 138, said armature 139 and conductor 140 for the armature 43 of the line relay 16, which armature 43 controls the circuit number one 20 for the line relay 15. Consequently, although the track relay 11 is deenergized and the line relay 16 is deenergized, the circuit for the line relay 15 includes the shunt established by the armature 139 of the 25 stick relay 19, so that said line relay 15 is energized to raise its armature 61. Since the signal 7 is in its danger position, the pole changing circuit controller 26 operated thereby is reversed so as to reverse the direction of the flow of current in the line relay 15. The armature 61 of said line relay 15 is raised regardless of the direction of flow of current, but the polar armature 66 is opened; and the signal 6 is operated to 35 its 45 degree or caution position.

The clearing of the signal 6 to its 45 degree position as soon as the train, moving in the direction indicated by the arrow X, passes entirely into the track section C, is 40 characteristic of the system disclosed in my prior application hereinbefore mentioned, and is also characteristic of the particular improvements in this system disclosed in my application, Serial No. 65,458 filed of even 45 date herewith, which improvements are intended to prevent the occurrence of the same undesirable condition hereinbefore described arising from the unusual reverse movement of the train. In the arrangement of controlling circuits shown and described in my 50 above mentioned prior applications, the intermediate signals corresponding to the signals 7 and 8 governing traffic in opposite directions are located opposite to each other, so that the signal 6, in being responsive to the presence of a train traveling in the direction indicated by the arrow X anywhere between the signal 6 and the signal 7, is also responsive to the presence of such a train anywhere 55 between said signal 6 and its opposing signal. In certain arrangements or locations of signals, however, it has been found expedient to locate corresponding intermediate signals governing traffic in opposite direc- 60

tions in a staggered relation, that is, in the 65 relative positions illustrated in the accompanying drawing; and in systems in which the signals are arranged in this staggered relation, according to the practice best known to me, the signal 6 does not control 70 as far as its opposing signal 8, in fact, not even beyond the signal 7; that is, a train anywhere in the track section B will cause said signal 6 to assume its stop position, even though said train is traveling in the direction indicated by the arrow X and the stick relay 19 is energized, but a train in the track section C will not cause the signal 6 to assume 75 its stop position. Consequently, in the unusual condition of traffic resulting from 80 the peculiar reverse movement hereinbefore described, a train, traveling in the direction indicated by the arrow X, after having entered the track section E and then reversed the direction of its movement, would have 85 to move clear back into the track section B before it would cause the signal 6 to assume its danger position.

For this reason it is necessary to make the 90 controlling circuits for the signal 6 such that this signal 6 will assume its stop position as soon as a train, having entered the track section E traveling in the direction indicated by the arrow X, reverses the direction 95 of its movement and enters the track section D. The presence of a train in the track section D, regardless of whence this train came, causes a deenergization of the track relay 12 and the line relay 16. In one case, if the stick relay 19 is energized, the deenergization of the line relay 16 and the dropping of its armature 43 has no effect on the line relay 15; whereas in the other case, when said stick relay 19 is deenergized, said armature 43 interrupts the circuit for the 100 line relay 15 and causes the signal 6 to assume a stop position. Referring particularly to the energizing circuit number five for the stick relay 19, it can be seen that this circuit is closed if either the armature 127 105 of the track relay 12 is in its upper position, or the signal 8 is in its stop position.

Bearing in mind this control of the stick 110 relay 19, and resuming the description of the operation, assume that the train in question traveling in the direction of the arrow X 115 passes entirely from the track section D into the track section E. As soon as the train leaves the track section D the track relay 12 is energized and its armature 127 raised. 120 Also, disregarding the action of the auxiliary relay Z and assuming the armature 74 thereof to be in its upper position, the circuit number four for controlling the line relay 17 is reestablished, thereby permitting the signal 8 to move to its 90 degree or proceed position and interrupt the second path for the 125 flow of current in circuits numbers five and

six through the circuit controlling arm 131. Consequently, if at this time the train in the track section E for some reason reverses the direction of its movement and returns to the track section D, the stick relay 19 will be deenergized, for the reason that the track relay 12 is deenergized and its armature 127 has broken the only remaining path for the flow of current in the stick circuit number six for the stick relay 19. When the stick relay 19 is deenergized, the shunt around the armature 43 of the line relay is broken, so that the line relay 15 is deenergized in correspondence with the deenergized condition of the line relay 16, and the signal 6 assumes its stop position. In this way, as soon as a train makes a reverse movement into the track section D it causes the signal 6 to assume its stop position. This is only true for trains traveling in the direction indicated by the arrow X and making a reverse movement in the direction indicated by the arrow Y, and rightly so, since for trains traveling in the opposite direction, the control of the signal 6 by the presence of a train on the track section D is unnecessary, there being an intermediate signal 7. This contingency is provided for by the operation of the stick relay 19, which, for trains traveling in the direction indicated by the arrow X and making a reverse movement, is energized and causes the signal 6 to be controlled by the track section D in the same way as hereinbefore explained; whereas, for trains traveling in the direction indicated by the arrow Y, said stick relay 19 is not energized.

Referring to the control of the signal 8, it can be seen from circuit number four that the line relay 17, controlling said signal 8, is controlled by the track sections B, C and D, by the pole changer magnet 32, and jointly by the armature 74 of the auxiliary relay Z and the armature 91 of the stick relay 19. The pole changer magnet 32 is controlled by the circuit controller 31 associated with the signal 5 and certain other controlling devices at the left, which are not necessary to consider, the part of the circuit for said pole changer magnet 32 which is shown being as follows: commencing at the common wire 35, conductors 36, 133 and 134, pole changer magnet 32, conductor 141, circuit controller 31 and conductor 142.

Assume that a train occupies the track section A, and disregarding for the moment the action of the auxiliary relay Z, it can be seen that the signal 8 will assume its 45 degree or caution position, since the signal 5 assumes its stop position and opens the circuit controller 31, which in turn deenergizes the pole changer magnet 32 and reverses the direction of flow of current in line relay 17. Consequently, at the time the train in the track section E is about to make a reverse movement, a train may occupy the track section

A and the signal 8 will only indicate caution. Likewise, until the first train actually enters the track section D the signal 6 will only indicate caution. In this way still remembering that the action of the auxiliary relay Z is disregarded, it would be possible to have two trains proceeding under caution signals entering the same space between two adjacent opposing signals, that is, two trains would enter the same stretch of track traveling in opposite directions without any intermediate signals to stop them. 70 75

In a system embodying this invention, however, the above mentioned undesirable condition cannot occur by reason of the action of the auxiliary relay Z, in connection with the armature 91 of the stick relay 19 and an armature 95 of the track relay 9 of the track section A. Assuming the same conditions as before, namely, that a train, 80 traveling in the direction indicated by the arrow X, has passed along the trackway into the track section E and desires to make a reverse movement; and that another train occupies the track section A. The stick relay 19 was energized by the passage of the first train, and one of the paths for the flow of current in the circuit number four for the line relay 17 is broken by the armature 91. The controlling circuit for the auxiliary relay Z is as follows: 85 90 95

Circuit number seven.

Commencing at the common wire 35, conductor 88, armature 34 of the pole changer 100 magnet 32, conductors 84 and 85, battery 21, conductors 86 and 87, armature 33 of the pole changer magnet 32, conductors 143, 82 and 96, armature 95 of the track relay 9 in its upper position, conductor 94, relay Z and 105 conductors 93, 68 and 55 back to the common wire 35.

From the circuit last traced it can be seen that the auxiliary relay Z is deenergized and its armature 74 is in its lower position whenever the track relay 9 is deenergized, that is, when a train occupies the track section A. Consequently, under the conditions assumed, both paths for the flow of current in circuit number four for the line relay 17 are interrupted, so that, regardless of the fact that the track sections B, C and D are unoccupied, the signal 8 will assume its stop position, thereby indicating to the engineer of the train in the track section E that he cannot make the reverse movement contemplated. It is considered preferable to arrange the signaling system so as to prevent the train intending to make the reverse movement from so doing rather than to cause 115 120 125 delay to any following train.

One important feature of this invention consists in arranging the controlling circuit for the line relay 17, which controls the signal 8 and which is drawn in heavy lines in 130

the drawing so that, when the stick relay 19 is energized by the passage of a train traveling in the direction indicated by the arrow X, said line relay 17 will be subject to the 5 control of the track relay 9 of the track section A, or of the track relays of other track sections to the left. It should also be noted that the stick relay 19 performs the function of selectively determining whether the 10 stop indication of the signal 8 shall be controlled by the track relay 9 of the track section A or by the track relays 10, 11 and 12 of the track sections B, C and D; and this selective action of the stick relay 19 is necessary, 15 since for trains traveling in the direction indicated by the arrow Y the stop indication of the signal 8 should be under the control of the track sections B, C and D only, whereas for trains traveling in the direction indicated by the arrow X and making the reverse move of the character before described, the stop indication of the signal 8 should be controlled by the track section A, as well as the track sections B, C and D. 20

25 One way of accomplishing the result above described is illustrated in the accompanying drawing; but, obviously, other modified arrangements of controlling circuits can be used; and in my co-pending application, Serial No. 65,458, filed the same date here-with, I have illustrated and described other ways of accomplishing the same result. I wish it to be understood that I contemplate the use of any one of the different arrangements of controlling circuits shown in said application in every case where such arrangements are applicable, including a system employing staggered intermediate signals. It is considered unnecessary to show 30 in detail the circuits showing the application of said modifications to the system having staggered intermediate signals, since such changes can be easily determined by one skilled in the art of railway signaling from 35 the disclosure in said application and the disclosure herein.

40 Another feature of the controlling circuits shown and described relates to the checking of the operation of the stick relays, and particularly the dropping of the armatures of 45 said stick relays, since it may happen that the armatures of one of the stick relays will, for some reason, fail to drop when it should. The necessity for such checking will be apparent 50 from a simple illustration. Assume a train is traveling in the direction indicated by the arrow Y from the track section E into the track section D. Under these conditions the energizing or pick up circuit for the 55 stick relay 20 is established, said circuit being as follows:

Circuit number eight.

Commencing at the battery 24, conductors 60 48², 47² and 145, circuit controller 30, con-

ductor 146, armature 147 of the track relay 12 in its lower position, conductor 148, armature 149 of the track relay 13 in its lower position, conductors 150 and 151, stick relay 20 and conductors 152 and 49² back to the 70 battery 24.

The armature 154 of the stick relay 20 closes a shunt comprising conductors 153, said armature 154 and conductor 155 for the armature 106 and its coöperating contacts 75 controlled by the line relay 17; and consequently, although the line relay 17 may be deenergized and its armature 106 in its lower position, the line relay controlling the next signal to the right corresponding to the 80 signal 8 and governing traffic in the direction indicated by the arrow Y, may be energized. Suppose that the train in question proceeds over the track section B through the track sections C and B and on to the siding S, and further suppose that the armatures of the stick relay 20 do not drop when the should, and that another train, traveling in the direction indicated by the arrow X enters the track section B. The deenergization of the track relay 10 and the dropping of its armature 40 would interrupt the circuit number four for energizing the line relay 17, as explained hereinbefore; and the armature 106 of said line relay should drop 90 and cause the deenergization of the line relay controlling the signal next to the right of the signal 8 and governing traffic in the same direction; but, since the armature 154 of the stick relay 20 is assumed to have remained 95 in its upper position, the armature 106 of said line relay 17 is shunted, and the signal to the right of the signal 8 does not assume its danger position, as it should. To avoid this objection, the controlling circuit 100 for the line relay 15 is arranged to include the armature 53 of the stick relay 20 in its lower position, so that, if the armatures of 105 said stick relay should improperly remain in their upper position, the signal 6 could 110 not assume its proceed position. In the same way, circuit number four for the line relay 17 includes the armature 80 of the stick relay 18 in its lower position. In short, the circuit for controlling each line relay associated 115 with each signal includes an armature in its lower position controlled by the stick relay associated with the next opposing signal.

Various changes may be made in the particular arrangements of circuits and controlling devices shown and described without departing from the invention or the physical embodiment thereof illustrated, and also this invention may be applied to other signaling systems. Also, although the particular embodiment of the invention shown is designed to be operated by direct current, simple modifications apparent to those skilled in the art of railway signaling, may 120 125 130

be made where alternating current may be used as an operating medium. The number of track sections into which the stretch of single track may be divided may be different 5 according to different conditions without affecting the application of this invention; and other signals for protecting the sidings, preliminary sections, and other expedients known in the art of railway signaling may 10 be combined with this invention.

Although I have particularly described the construction of one physical embodiment of my invention, and explained the operation and principle thereof; nevertheless, I desire 15 to have it understood that the form selected is merely illustrative, but does not exhaust the possible physical embodiments of the idea of means underlying my invention.

What I claim as new and desire to secure 20 by Letters Patent of the United States, is:

1. In a signaling system for railways, in combination: a stretch of trackway divided into electrically isolated track circuited sections, each having a track relay; a first signal 25 and a second signal governing traffic in opposite directions over said stretch; a circuit controller governed by said second signal and closed when it is in its stop position; a shunt for said circuit controller which is 30 closed when the track relay of the section adjacent to said second signal and protected thereby is energized; and a controlling device for said first signal having an operating circuit including said circuit controller.

2. In a signaling system for railways, in combination: a stretch of trackway divided into electrically isolated track circuited sections, each having a track relay; a first and 35 a second signal for governing traffic in opposite directions over said stretch; means controlled by the track relay of the section succeeding the section protected by said first signal for causing said first signal to assume its stop aspect; means set into operation 40 by the movement of a train in the direction of traffic governed by said first signal for rendering said first means ineffective; and a circuit for controlling said second means, said circuit being controlled jointly by said 45 second signal and by the track relay of the section protected thereby, said circuit being broken and said second means being idle when said second signal assumes an aspect other than its stop aspect and said track 50 relay is deenergized.

3. In a signaling system for railways, in combination: a stretch of trackway divided into electrically isolated track circuited sections, each having a track relay; a first and 55 a second signal for governing traffic in opposite directions over said stretch; means controlled by the track relay of the section succeeding the section protected by said first signal for causing said first signal to assume its stop aspect; means set into operation by

the movement of a train in the direction of traffic governed by said first signal for rendering said first means ineffective; a circuit for controlling said second means, said circuit being controlled jointly by said second signal and by the track relay of a section protected thereby, said circuit being broken and said second means being idle when said second signal assumes an aspect other than its stop aspect and said track relay is deenergized; means governed by the track relay of a section in advance of the second signal and beyond the first signal for exerting a controlling influence suitable for causing the second signal to indicate stop; and means 75 operated by said second mentioned means for rendering said last-mentioned means to be effective to control said second signal when a train travels in the direction of traffic protected by said first signal. 85

4. In a signaling system for railroads, the combination with a stretch of single track having a passing siding and divided into track sections each provided with a track circuit, of a signal located adjacent to one 90 end of the siding and governing traffic away from the siding, a second signal in advance of the first signal and governing traffic in the same direction, a third signal in advance of the second signal and governing traffic in 95 the opposite direction, and controlling circuits and devices for causing the stop control of the first signal to extend up to the second signal when a train travels away from the siding and up to the third signal 100 whenever a train passes the third signal while traveling toward the siding.

5. In a signaling system for railways, in combination: a stretch of trackway divided into electrically isolated track circuited sections, each having a track relay; a first and a second signal for governing traffic in opposite directions; a device for controlling the first signal; a controlling circuit for said device having two conducting paths arranged in multiple; means for interrupting one of said paths by a movement of the train along said stretch entirely by said second signal in the direction of traffic governed by said first signal; and means for 105 interrupting the other of said conducting paths by the presence of a train on the section adjacent to said second signal and protected thereby. 110

6. In a signaling system for railroads, the combination with a stretch of track divided into a plurality of track sections each provided with a track circuit, of a stick relay, a pickup circuit for said stick relay acting to cause energization thereof when a train 120 travels in one direction over said stretch, a stick circuit for maintaining said relay energized after it has been initially energized 125 and so long as a train occupies said stretch, and means for controlling the continuity of 130

- said stick circuit in accordance with the direction of movement of trains on to an intermediate track section of said stretch, whereby said stick relay will be energized and maintained energized for one direction of train movement, but will be automatically deenergized when a train making such movement reverses its direction of travel at an intermediate point in the stretch of track.
- 5 7. In a signaling system for railroads, the combination with a stretch of single track divided into track circuit sections and having a passing siding, of a signal located adjacent to one end of the siding and governing traffic away from the siding, a second signal in advance of the first signal and governing traffic in the same direction, a third signal in advance of the second signal and governing traffic in the opposite direction, a signal circuit for controlling each signal, means for normally causing the signal circuit of the first signal to be subjected to the same control as the signal circuit for the second signal, an electrically operable circuit controlling device for rendering said means ineffective, and controlling circuits governed by certain track circuit sections of the stretch for placing said device in its active condition when a train moves in the direction away from the siding and for maintaining said device in its active condition until such train in continuing its movement has advanced to a predetermined point in advance of the second signal and beyond the third signal, said controlling circuits causing said device to automatically resume its inactive condition when such train reverses its direction of movement and travels toward the siding past the third signal.
- 10 8. In a signaling system for railroads, the combination with a stretch of single track divided into track circuit sections and having a passing siding, of a signal located adjacent to one end of the siding and governing traffic away from the siding, a second signal in advance of the first signal and governing traffic in the same direction, a third signal in advance of the second signal and governing traffic in the opposite direction, means tending to cause the first signal to indicate stop when a portion of the track in advance of the second signal and extending beyond the third signal is occupied by a train, a normally deenergized stick relay, means controlled by said stick relay for rendering said means ineffective, a pickup circuit for said stick relay adapted to cause energization thereof when a train moves in the direction of traffic governed by the first and second signals, a stick circuit adapted to maintain said stick relay in its energized condition until such train has moved out of said portion of track, said stick circuit including two branches in multiple, a circuit controller included in one of said branches
- 15 and open when the track circuit section adjacent to the third signal and in advance thereof is occupied, and another circuit controller included in the other of said branches and closed only when the third signal indicates stop.
- 20 9. In a signaling system for railroads, the combination with a stretch of single track divided into track circuit sections, of a signal for governing traffic in one direction, means tending to cause said signal to indicate stop when a predetermined portion of the track in advance thereof is occupied, an electrically operable device adapted when changed from its normal condition to render said means ineffective, and controlling circuits and apparatus for governing said device and adapted to cause said device to change from its normal condition when a train travels in the direction of traffic governed by the signal and to remain in its changed condition while such train occupies said portion of the track, said controlling circuits and apparatus being also adapted to cause the device to automatically resume its normal condition when such train reverses its direction of movement after having entered such portion of track.
- 25 10. In a signaling system for railroads, the combination with a stretch of single track having a passing siding and divided into track sections each provided with a track circuit, of a signal located adjacent to one end of the siding and governing traffic away from the siding, a second signal in advance of the first signal and governing traffic in the same direction, a third signal in advance of the second signal and governing traffic in the opposite direction, a signal circuit for controlling each signal, means for normally causing the signal circuit of the first signal to be subjected to the same control as the signal circuit for the second signal, an electrically operable circuit controlling device for rendering said means ineffective, said device being automatically operated by a train moving away from the siding and being maintained in its operated condition until such train has progressed to a predetermined point in advance of the second signal and beyond the third signal, controlling circuits for causing said device to automatically resume its non-operated condition when a train causing its operation reverses its direction of movement after advancing beyond the second signal, and means rendered effective by the operation of said device for controlling the signal circuit of the third signal from a track circuit located adjacent to and between the ends of the siding.
- 30 11. In a signaling system for single track railroads provided with track circuit sections, the combination with a signal for governing traffic, of an electrically operable

- device for governing said signal, controlling circuits and apparatus for causing said device to change from its normal condition only when a train travels in the direction of traffic governed by the signal and to remain in its changed condition until such train has advanced a predetermined distance in advance of the signal, said controlling circuits and apparatus also automatically causing said device to resume its normal condition when such a train effecting such change reverses its direction of movement. 65
12. In a signaling system for single track railroads provided with track circuit sections, the combination with a first signal and a second signal for governing traffic in opposite directions, a stick relay associated with the first signal, means for energizing said stick relay when a train travels in the direction of traffic governed by the first signal, a stick circuit for said relay controlled by the track circuit sections protected by the first signal and including two branches in multiple, a circuit controller included in one of said branches and opened when a particular track circuit section adjacent to the second signal and in advance thereof is occupied, and a slow-acting circuit controller included in the other of said branches and closed when any one of a plurality of track sections in advance of the second signal and including said particular track circuit section is occupied. 70
13. In a signaling system for railroads, the combination with a stretch of single track divided into track circuit sections having a passing siding, of a signal located adjacent to one end of the siding and governing traffic away from the siding, a second signal in advance of the first signal and governing traffic in the same direction, a third signal in advance of the second signal and governing traffic in the opposite direction, means tending to cause the first signal to indicate stop when any portion of the track between the second and third signals is occupied, an electrically operable device responsive to the direction of movement of trains and acting when changed from its normal condition to render said means ineffective, said device being automatically changed from its normal condition when a train travels in the direction of traffic governed by the first and second signals and being maintained in its changed condition until such train has advanced to a predetermined point in advance of the second signal and beyond the third signal, means for causing said device to automatically resume its normal condition when such train causing such change reverses its direction of movement after passing the third signal, means capable of exerting a controlling influence suitable for causing the third signal to indicate stop when a train occupies a portion of the track adjacent to the siding and between the ends thereof, and means acting when said device is in its changed condition to permit said last mentioned means to exert its controlling effect on the third signal effectively. 75
14. In a signaling system for railroads, the combination with a stretch of single track divided into track circuit sections and having a passing siding, of a first signal located adjacent to one end of the siding and governing traffic away from the siding, a second signal located in advance of the first signal and governing traffic in the same direction, a third signal located in advance of the second signal and governing traffic in the opposite direction, and controlling circuits and apparatus for governing the first signal and acting to cause the stop control of said signal to normally extend only up to the second signal for trains traveling in the direction away from the siding, said controlling circuits and apparatus including means for automatically causing the stop control of said signal to extend up to the third signal when a train travels in the direction away from the siding entirely beyond the third signal and then reverses its direction of movement. 80
15. In a signaling system for railroads, the combination with a stretch of single track divided into track circuit sections and having a passing siding, of a first signal located adjacent to one end of the siding and governing traffic away from the siding, a second signal located in advance of the first signal and governing traffic in the same direction, a third signal located in advance of the second signal and governing traffic in the opposite direction, controlling circuits and apparatus for governing the first signal and acting to cause the stop control of said signal to normally extend only up to the second signal for trains traveling in the direction away from the siding, said controlling circuits and apparatus including means for automatically causing the stop control of said signal to extend up to the third signal when a train travels in the direction away from the siding entirely beyond the third signal and then reverses its direction of movement. 85
16. In a signaling system for railroads, the combination with a stretch of single track divided into track circuit sections and having a passing siding, of a first signal located adjacent to one end of the siding and governing traffic away from the siding, a second signal located in advance of the first signal and governing traffic in the same direction, a third signal located in advance of the second signal and governing traffic in the opposite direction, controlling circuits and apparatus for governing the first signal and acting to cause the stop control of said signal to normally extend only up to the second signal for trains traveling in the direction away from the siding, said controlling circuits and apparatus including means for automatically causing the stop control of said signal to extend up to the third signal when a train travels in the direction away from the siding entirely beyond the third signal and then reverses its direction of movement. 90
17. In a signaling system for railroads, the combination with a stretch of single track divided into track circuit sections and having a passing siding, of a first signal located adjacent to one end of the siding and governing traffic away from the siding, a second signal located in advance of the first signal and governing traffic in the same direction, a third signal located in advance of the second signal and governing traffic in the opposite direction, controlling circuits and apparatus for governing the first signal and acting to cause the stop control of said signal to normally extend only up to the second signal for trains traveling in the direction away from the siding, said controlling circuits and apparatus including means for automatically causing the stop control of said signal to extend up to the third signal when a train travels in the direction away from the siding entirely beyond the third signal and then reverses its direction of movement. 95
18. In a signaling system for railroads, the combination with a stretch of single track divided into track circuit sections and having a passing siding, of a first signal located adjacent to one end of the siding and governing traffic away from the siding, a second signal located in advance of the first signal and governing traffic in the same direction, a third signal located in advance of the second signal and governing traffic in the opposite direction, controlling circuits and apparatus for governing the first signal and acting to cause the stop control of said signal to normally extend only up to the second signal for trains traveling in the direction away from the siding, said controlling circuits and apparatus including means for automatically causing the stop control of said signal to extend up to the third signal when a train travels in the direction away from the siding entirely beyond the third signal and then reverses its direction of movement. 100
19. In a signaling system for railroads, the combination with a stretch of single track divided into track circuit sections and having a passing siding, of a first signal located adjacent to one end of the siding and governing traffic away from the siding, a second signal located in advance of the first signal and governing traffic in the same direction, a third signal located in advance of the second signal and governing traffic in the opposite direction, controlling circuits and apparatus for governing the first signal and acting to cause the stop control of said signal to normally extend only up to the second signal for trains traveling in the direction away from the siding, said controlling circuits and apparatus including means for automatically causing the stop control of said signal to extend up to the third signal when a train travels in the direction away from the siding entirely beyond the third signal and then reverses its direction of movement. 105
20. In a signaling system for railroads, the combination with a stretch of single track divided into track circuit sections and having a passing siding, of a first signal located adjacent to one end of the siding and governing traffic away from the siding, a second signal located in advance of the first signal and governing traffic in the same direction, a third signal located in advance of the second signal and governing traffic in the opposite direction, controlling circuits and apparatus for governing the first signal and acting to cause the stop control of said signal to normally extend only up to the second signal for trains traveling in the direction away from the siding, said controlling circuits and apparatus including means for automatically causing the stop control of said signal to extend up to the third signal when a train travels in the direction away from the siding entirely beyond the third signal and then reverses its direction of movement. 110
21. In a signaling system for railroads, the combination with a stretch of single track divided into track circuit sections and having a passing siding, of a first signal located adjacent to one end of the siding and governing traffic away from the siding, a second signal located in advance of the first signal and governing traffic in the same direction, a third signal located in advance of the second signal and governing traffic in the opposite direction, controlling circuits and apparatus for governing the first signal and acting to cause the stop control of said signal to normally extend only up to the second signal for trains traveling in the direction away from the siding, said controlling circuits and apparatus including means for automatically causing the stop control of said signal to extend up to the third signal when a train travels in the direction away from the siding entirely beyond the third signal and then reverses its direction of movement. 115
22. In a signaling system for railroads, the combination with a stretch of single track divided into track circuit sections and having a passing siding, of a first signal located adjacent to one end of the siding and governing traffic away from the siding, a second signal located in advance of the first signal and governing traffic in the same direction, a third signal located in advance of the second signal and governing traffic in the opposite direction, controlling circuits and apparatus for governing the first signal and acting to cause the stop control of said signal to normally extend only up to the second signal for trains traveling in the direction away from the siding, said controlling circuits and apparatus including means for automatically causing the stop control of said signal to extend up to the third signal when a train travels in the direction away from the siding entirely beyond the third signal and then reverses its direction of movement. 120
23. In a signaling system for single track railroads provided with track circuit sections, an electrically operable device, con-

trolling circuits and apparatus for causing said device to be changed from its normal condition when a train travels in one direction over the track and to be maintained in 5 its changed condition so long as such train occupies a predetermined portion of the track, means for causing said device to automatically resume its normal condition

when a train traveling in said direction and causing said device to change from its normal condition reverses its direction of movement after having entered said predetermined portion of track, and a circuit for signaling controlled by said device. 10

SEDGWICK N. WIGHT.
